Henning S. Hermanson, Deerfield, and Frederick D. Joesting, Oak Park, Ill., assignors to Minneapolis-Honeywell Regulator Company, Minneapolis, Minn., a corporation of Delaware

Application March 22, 1946, Serial No. 656,274

16 Claims. (Cl. 98—101)

1

Our present invention relates to a register adapted for hot air heating systems, cooling systems or ventilating systems in residences, places of business and the like and particularly where forced air circulation is utilized for effecting proper flow of air into the various rooms through comparatively small area ducts which may be located between opposite surfaces of ordinary walls.

One object of the invention is to provide a damper supporting frame which is mounted in such manner that a grille thereon can project from the wall surface without however projecting to such an extent that it detracts from the appearance of the wall, a damper arrangement being provided within the grille for permitting or stopping flow of air from the duct as desired.

Another object is to provide a damper blade arrangement which equalizes the flow from the register regardless of the position at which the damper blades are adjusted so that adjustment does not change the flow pattern established during installation of the control damper and grille.

Still another object is to provide a grille of simple and inexpensive construction in which the grille bars are actually deflector or diffuser blades that can be so adjusted at the time of installation as to provide a desired lateral air distribution pattern, thereby providing for even distribution throughout the room regardless of whether the grille is centered with respect to a wall therein or off-center in the wall.

A further object is to provide a turning vane assembly designed for low pressure drop and therefore maximum efficiency, the assembly being supported on the damper frame and located in the duct so as to also properly turn and distribute the air vertically with respect to the damper structure and the grille.

Still a further object is to provide a means for supporting the turning vane assembly so that it can be adjusted at the time of installation for either a thick or a thin wall, the vanes being positioned with relation to the duct at either adjustment for effecting proper vertical distribution of the air stream.

An additional object is to provide a linkage arrangement for opening the damper blades or for closing them as at night which arrangement is comparatively simple, involving a minimum number of parts and those parts being entirely carried by the damper blades without the necessity of any stationary pivot brackets or the like,

thus effecting an efficient operation of the damper blades without any binding, and a stop for the maximum open position being provided which is adjusted only at the time of installation to balance out each register relative to all other registers in the system.

Another additional object is to provide a hinge structure for the damper blades which provides a seal through the hinges of the blades when they are closed, thus preventing any whistling sounds as ordinarily encountered where forced circulation is stopped by closed blades that have piano or other types of hinges that leave cracks through which the air flows at high velocity when the dampers are closed, and for securing a good air stream characteristic, that is one in which there is a single main air stream and no secondary air streams as through hinge joints to cause turbulence and disturbance to the main air stream.

With these and other objects in view, our invention consists in the construction, arrangement, and combination of the various parts of our device whereby the objects contemplated are attained, as hereinafter more fully set forth, pointed out in our claims, and illustrated in the accompanying drawings, in which:

Figure 1 is a perspective view of a register embodying our present invention and showing only the portion that projects beyond the wall in which the register is mounted.

Figure 2 is an exploded isometric view of parts of the boot and grille frame forming part of the register to show their relative shapes and positions.

Figure 3 is an inside rear elevation of slightly more than one-half of the register structure with the turning vanes omitted and end brackets for the turning vanes shown in section.

Figure 4 is a sectional view on the line 4—4 of Figure 3 showing the dampers in the register closed.

Figure 5 is a sectional view on the line 5—5 of Figure 4 to show portions of the damper operating linkage, this view being the reverse side of the linkage shown at the left hand end of Figure 3.

Figure 6 is an isometric view showing the completion of a register assembly comprising a grille assembly and a boot assembly, one end only of the assembly being shown as it is substantially the same at both ends.

Figure 7 is a sectional view similar to Figure 4 showing the dampers in opened position.

Figure 8 is a similar sectional view showing the

dampers closed and the linkage moved to an intermediate position between the positions of Figures 4 and 7.

Figure 9 is an isometric view showing an inside view of a stop element for the damper operating lever.

Figure 10 is a plan view partly in section of a grille assembly and a boot assembly in partially dis-assembled position, with a turning vane assembly shown in dot and dash lines.

Figure 11 is an enlarged sectional view at the center of the grille showing deflector blades and a tool for changing the angle of the blades as required for a particular register installation.

Figure 12 is a rear elevation of one end of a grille assembly showing the position of a sealing gasket by dot and dash lines.

Figure 13 is a rear elevation of one end of a boot assembly adapted to be superposed on the grille assembly of Figure 12 for forming the complete register.

Figure 14 is a sectional view on the line 14-14 of Figure 12 showing the association of a grille and a grille frame to form a grille assembly.

Figure 15 is a sectional view on the line 15-15 of Figure 13 to show the association of a boot and a boot end.

Figure 16 is a developed view of a flat sheet of material shaped and punched prior to forming into a grille of our register.

Figure 17 is a sectional view similar to Figure 4 showing only a boot assembly and a turning vane assembly and illustrating the turning vane assembly installed in a position for a thick wall and by dot and dash lines installation in a position for a thin wall.

Figure 18 is an isometric view showing a boot end and by dotted lines a turning vane supporting bracket associated therewith.

Figure 19 is a rear elevation of one corner of the boot to show its shape prior to assembly.

Figures 20 and 21 are enlarged sectional views on the lines 20-20 and 21-21 respectively of Figure 19 showing a boot flange and a hinge element thereof, Figure 21 also showing the coaction of a damper blade with the hinge element, and Figure 22 is a sectional view similar to Figure 21 showing a position that the parts assume during assembly of a damper blade to a boot of our register.

On the accompanying drawings we have used the reference character F to indicate a grille frame, G a grille, B a boot, and A a boot end. These are the four major parts of our register, in addition to which a vane assembly comprising vanes V and end brackets C for supporting the vanes complete the register assembly with the exception of damper blades D and minor parts which will hereinafter be described in detail.

The frame F is formed of sheet metal and consists of a rectangular frame-like portion having a pair of vertical elements 10 and a pair of horizontal elements 12 lying in a plane parallel to a wall W on which the register is mounted. The frame elements 10 and 12 are provided with a peripheral flange 13 bent rearwardly or to the left in Figure 4 and upper and lower walls 14 and 16 bent forwardly or to the right in Figure 4. The walls 14 and 16 have flanges 18 bent toward each other.

The frame element 10 of the grille frame F is provided with a central ear 20 and a pair of ears 22 on opposite sides thereof initially in the shape shown in Figure 2 but bent up to the dotted shape

prior to assembly of the grille G and the boot B with respect to the grille frame.

The grille G comprises a sheet of initially flat metal slightly more than half of which is shown in Figure 16. This sheet has a series of holes 21 punched adjacent opposite side edges thereof and between the two series of holes the sheet is periodically slit as indicated at 24. At each end of the sheet a pair of flanges 23 and 25 are provided. The flanges 25 have openings 26 and a wide notch 28. The width of the notch 28 is substantially equal to the width of the ear 20 of the grille frame F. Along the sides of the sheet a plurality of spot welding ears 30 are provided, and at the center of the sheet a vertical slot 32 is provided.

The sheet of Figure 16 is formed to the desired shape to form a grille by bending the marginal edges 34 at right angles to the body of the sheet as on the line 39 to serve as attaching flanges cooperating with the top and bottom walls 14 and 16 of the grille frame F. The flanges 34 are also bent to assume the shape of the flanges 18 of the grille frame which shape is perhaps best shown in Figures 1 and 10, and the portions of the sheet between the slits 24 form deflector blades 36 which are bent out of the surface of general curvature of the sheet as to the positions shown in Figure 10. These blades are adjustable at the time of installation by the application of a slotted tool 38 thereto (see Fig. 11) which may be used to readily bend the blades to the desired angle to secure a desired lateral air distribution pattern. The punched openings 21 leave narrow connecting portions 40 which serve to keep the deflector blades 36 as an integral part of the grille G yet permit a limited number of bendings to place them at the proper deflection angle at the time of installation of the register after which, of course, they remain permanently in position.

The boot B comprises a rectangular frame-like sheet of metal having horizontal frame elements 42 and vertical frame elements 44. A peripheral flange 46 extends rearwardly from the frame elements 42 and 44. Along the inner edges of the frame elements 42, somewhat wider boot flanges 48 are formed which extend rearwardly. These boot flanges terminate in slightly curved edges 50 and each edge is provided with a further curved hinge portion 52. The hinge portions 52 are adapted to receive the damper blades D which blades are provided with rolled edges 58 to rotate in the hinge elements 52 and closely fit the curved flanges 50 to prevent air passage at this point, particularly when the dampers are closed. The damper blades D are substantially flat with their outer or forward edges only slightly curved as illustrated at 60 to provide for maximum strength and smooth air flow from a forced circulation system for which our register is particularly designed.

The boot B at each end is provided with a slot 62, the purpose of which will hereinafter appear. Each end of each boot flange 48 is provided with an ear 64 to coact with the boot end A. The boot end A consists of an angle shaped member having flanges 66 and 68 as shown in Figure 2 bent at right angles to each other. The flange 66 is provided with a narrow ear 70 and a wide offset ear 72. The flange 66 is also provided with a pair of slots 74 and a pair of ears 76, the purpose of which will hereinafter appear. The flange 68 is provided with a long notch 78 which is equal in length to the distance between the 75 outside edges of the ears 22 of the frame F.

After the various parts thus far described are formed they are assembled in the following described manner:

Two sub-assemblies are first made. One is the grille assembly and the other is the boot assembly. The assembly of the grille consists of moving the grille G in the general direction of the arrow 80 in Figure 2 and then down with the notch 28 receiving the ear 20 and the slots 26 receiving the ears 22 which of course are first bent up to the dotted position. The grille G is then secured to the grille frame F, being spot welded at the six ears 30 and at two points on each flange 25, for instance midway between the slots 26 and the ends of the flange. The grille assembly will then appear in rear elevation as shown in Figure 12.

The boot assembly is made up by moving the boot ends A toward the ends of the boot B as indicated by the arrow 82 in Figure 2 and associating them with the ears 64 which are received through the slots 74. The ears 64 are then twisted as shown in Figures 3 and 6 to retain the boot ends in position. A rear elevation of one end of the boot assembly will then appear as in Figure 13.

Each damper blade D is next installed by hooking its rolled edge 58 in the hinge elements 52 as shown in Figure 22 and then swinging the blade as indicated by the arrow 53 around to the position of Figure 21. The ears 76 of the boot ends may then be bent inwardly as shown in Figures 3 and 13 to take up end play on the damper blades. This completes the boot assembly and a rear elevation thereof will appear as in Figure 13.

The boot assembly is now associated with the grille assembly by moving the boot assembly as indicated by the arrow 84 in Figure 2 (or upwardly in Figure 10 where the parts are in such position that the ears 20 and 22 have entered the slot 62 of the boot and are about to enter the notch 78 of the boot end). When the parts are fully brought together they will appear as in Figure 14 and also as in Figure 3 except that the ears 20 and 22 at this time are extended toward the observer of Figure 3 instead of being bent against the boot end A. The final assembly operation is to bend them down as shown in Figures 3 and 6, this of course being done at each end of the register, and the grille and boot assembly is then complete.

The peripheral flange 46 of the boot B serves as a positioning means for a gasket 86 of sponge rubber or the like adapted to serve as a seal against the wall W to prevent air leakage around the register. The completed register itself is mounted by means of screws 88 through openings 90 in each of the wall portions 19 of the frame F. These screws may extend into flanges 92 of a duct D' or any suitable element mounted to receive the screw in such manner that the register can be drawn toward the wall W and compress the gasket 86.

We provide a third assembly which may be termed a "turning vane assembly" and which comprises turning vanes V and supporting brackets C. The vanes are supported with relation to the brackets by means of two ears 94 at each end of each vane, which ears extend through notches 96 in the brackets and are then bent over to retain the vanes and brackets in assembled relation to each other. In each bracket there are five of the notches 96 and a slot 97 for receiving the six ears 94 of the three vanes V.

Each vane supporting bracket C is also provided with a pair of narrow notches 98 and 99 in its upper edge and a pair of wide notches 100 and 101 in its lower edge. As shown in Figure 18 the notch 100 is adapted to coact with the offset ear 72 of the boot end A and the narrow notch 98 is adapted to register with the ear 70 after which the ear 70 is bent into the notch 98 and then down against the bracket C. Thus each bracket may be assembled to its respective boot end and supported in position for a duct D' located in a thin wall, that is one plastered or otherwise treated with a thin wall surface as shown by dot and dash lines in Figure 17, or if the duct is located as shown at D'' for a thick wall then the brackets can be set further rearwardly so that the ears 72 and 70 of the boot ends A coact with the wide and narrow notches 101 and 99 respectively of the vane supporting brackets C. The vanes will in either case be approximately centered relative to the duct. The turning vane assembly is thereby adjustable at the time of installation for either a thin wall or a thick wall and of course after installation the ears 70 bent into the notches 98 retain the turning vane assembly permanently in the installed position.

Some means must be provided to conveniently move the damper blades D to the closed position of Figure 4 or to the open position of Figure 7. We have provided a damper linkage arrangement entirely mounted on the damper blades and having an operating lever projecting through the central slot 32 of the grille G. The operating lever is shown at 102. The lever 102 has a pair of pivots 104 and 106. On the pivot 104 a link 108 is pivoted intermediate its ends and at its lower end it is pivoted at 110 to the lower damper blade D. The pivot 110 is in the form of a pin having its ends spot welded at 113 to the lower damper blade. Its upper end is pivoted at 112 to a damper lever 114 which lever has a foot 115 secured to the upper damper blade, as by spot welding indicated at 117. The pivot 106 of the operating lever 102 is then connected by a link 116 to a pivot 118 carried by the damper lever 114.

The link 116 as best shown in Figure 3 has a loop or U-shaped portion 120 formed therein to give it some degree of resiliency for positively retaining the dampers closed due to the pivot 106 passing over-center relative to a line between the pivots 104 and 118, the dead-center position being shown in Figure 8. In closing the dampers they are in the closed position when the linkage is in the position of Figure 8 and further upward movement of the outer end of the operating lever 102 from the position of Figure 3 to the position of Figure 4 causes the U-shaped portion 120 to expand again and lock the blades in closed position when the linkage reaches the position shown in Figure 4.

In returning from the position of Figure 4 to the position of Figure 7 the dead-center position of Figure 8 is passed through and the operating lever 102 lowered to the wide open position of the dampers as shown in Figure 7. A spring 122 connects a lug 124 of the link 108 to a lug 126 of the damper lever 114 to constrain the damper blades toward their wide open position and the resiliency of this spring keeps them in that position against any vibration or closing tendency.

The character of the link 116 is such that it is also adjustable at the time of installation to secure the desired degree of over-center "snap"

and compensate for variations in manufacture. The U-shaped portion 120 can be opened wider to increase the snap or closed in small increments to decrease the snap if there is too much snap.

To clear the operating lever 102 the upper damper blade D is provided with a notch 127 and the lower damper blade is provided with a notch 129 as shown in Figure 5.

A stop 128 is provided for the maximum open position of the dampers which position may be as in Figure 7 or some position less open such as shown by dotted lines if the stop 128 is adjusted for instance to the dotted position shown. The stop 128 is a square of metal having an ear 130 received in the slot 32 of the grille to keep the stop from turning. The stop is threaded to receive a screw 132, the head of which is on the outside of the grille. A washer 134 is interposed between the grille and the stop 128. The screw 132 may be loosened for permitting shifting of the position of the stop, and then retightened for clamping the stop to the grille adjacent the edges of the slot 32, these edges being gripped between the washer 134 and the head of the screw.

At the time of installation the engineer determines the proper degree of opening for the damper blades to balance out with respect to the other registers in the installation and of course the dampers of each register are thus properly adjusted in relation to every other damper depending upon the size of the room, the distance of the register from the air circulating blower and other factors. Thereafter the householder has only two settings: (1) Opened to the maximum position determined by the stop 128 when heat is desired or (2) completely closed when heat is not desired, for instance as required at night time in a bedroom.

Our register has a number of advantages as will be obvious from the foregoing specification, one of which is simplicity of construction and assembly. The grille G has the advantage of being formed of a single sheet of metal which can be shaped and assembled in relation to the grille frame F, after which the assembly of boot and boot ends together with damper blades may be positioned on the grille assembly and the assembly of all five of these parts completed by bending of six ears 20 and 22.

The turning vane assembly can be quickly positioned and retained in position by the simple expedient of bending the two ears 70 to their retaining positions. The turning vane assembly can be adjusted at the time of installation to accommodate either a thick wall or a thin wall. By having the ear 72 and the notches 100 and 101 relatively wide while the ear 70 and the notches 98 and 99 are relatively narrow there is no possibility of installing the vanes wrong-side-up. The register itself is always installed with the stop 128 down.

The turning vanes may be omitted from some installations. This is a further reason for having the turning vane assembly separate from the register so that the vane assembly can be used or not as required.

The duct D' is mounted in the wall W at the time it is built, after which the wall is plastered and after the plaster is dry the register assembly is installed by the heating engineer. The boot and grille assembly are completed at the factory, and on the job the engineer installs the turning vane assembly (if used) in the proper position for either a thick wall or a thin wall. Aside

from these operations, the only other operation for installation is the insertion of the screws 88 through the openings 90 of the register and into the flange 92 of the duct. These are preferably metal piercing screws to facilitate installation.

The heating engineer then adjusts the deflector blades 36 (which were delivered to the job set approximately at the angles in Figure 10) so as to get the proper lateral air distribution depending upon the shape of the room, its position in relation to the register and other factors. He also adjusts the stop 128 and this completes the installation and adjustments of the entire register.

Some changes may be made in the construction and arrangement of the parts of our device without departing from the real spirit and purpose of our invention, and it is our intention to cover by our claims any modified forms of structure or use of mechanical equivalents which may be reasonably included within their scope.

We claim as our invention:

1. In a register, a grille frame having ears at the ends thereof, a grille mounted in said frame and having slots and notches receiving said ears, a boot frame having slots receiving said ears, boot ends having slot and ear connection with said boot frame, said ears of said grille frame being bent over the edge of said boot ends to retain the grille and boot frame assembled, a pair of damper blades hinged to said boot frame, said boot ends having ears arranged to contact the ends of said damper blades to limit end play thereof.
2. In a register, a grille frame having ears at the ends thereof, a grille mounted in said frame and having slots and notches receiving said ears, a boot structure having slots receiving said ears, said ears being bent over to retain said grille and boot structure assembled, and a pair of damper blades hinged to said boot structure and mounted therein.
3. In a register, a grille frame having ears at the ends thereof, a grille mounted in said frame and having slots receiving said ears, a sub-frame boot structure having slots receiving said ears, said ears being bent to retain the grille and boot structure assembled, a pair of damper blades hinged to said boot structure, and a turning vane assembly comprising end brackets and turning vanes having their ends connected to said brackets, said brackets being supported on said boot structure.
4. In a register, a grille frame having a grille mounted in said frame, a boot structure for said frame, boot ends connected with said boot structure, and a pair of damper blades hinged to said boot structure, said boot ends having ears to contact the ends of said damper blades to limit end play thereof.
5. In a register, a grille frame, a grille and a flanged boot structure mounted in said frame, boot ends connected with said boot structure, a pair of damper blades hinged to said boot structure, and a turning vane assembly comprising end brackets and turning vanes having their ends connected to said brackets, said boot ends having ears and said brackets having notches for co-action therewith for supporting said turning vane assembly on said register, said notches of said brackets being plural in number for selective co-action with said ears of said boot ends for installation of said turning vanes at different spacing in relation to said grille.
6. In a register having an opening for air therethrough and having a frame around said open-

ing; rearwardly extending flanges attached to said frame and arranged near the top and bottom of said opening, the rearmost edges of said flanges being curved; damper blades having rolled edges fitting said curved edges to form a hinged connection of said damper blades to said flanges; and means for adjusting said damper blades toward and away from each other comprising a damper operating lever having an outer end and an opposite end, a damper blade lever connected to one damper blade, a link pivoted to said last lever and to the other damper blade, said damper operating lever being pivoted on and supported by said link, a pivot arranged at a point on the opposite end of said operating lever spaced from the pivotal mounting of said operating lever, and a second link connecting said last pivot to a pivot on said damper blade lever spaced rearwardly from the pivotal connection of said first link thereto, said second link having a U-shaped bend therein to give resiliency to the link in an over-center position with the damper blade closed, the adjacent edges of said blades being notched to clear said damper operating lever.

7. In a register having an opening for air therethrough and having a frame around said opening; a pair of rearwardly extending flanges attached to said frame, one flange being near the top and the other flange being near the bottom of said opening; a pair of damper blades; means hinging one edge of one of said blades to the rear edge of one of said flanges and the other of said blades to the rear edge of the other of said flanges, said damper blades being arranged to control air flow through said opening; and linkage means for opening and closing said damper blades, said linkage means comprising a damper operating lever having an outer end, a damper blade lever rigidly connected to one damper blade and having a remote end, a link pivoted to an intermediate portion of said last lever and to the other damper blade, said damper operating lever being pivoted on and supported by said link, a pivot at a point spaced along said operating lever from the pivotal mounting of said lever and in a direction away from the outer end of said operating lever, and a second link connecting said last pivot to a pivot on the remote end of said damper blade lever and spaced from the pivotal connection of the first link thereto.

8. In a register having an opening for air therethrough and having a frame around said opening; a pair of flanges attached to said frame and extending rearwardly therefrom, one flange being near the top and the other flange being near the bottom of said opening; a pair of damper blades; means hinging an edge of one of said blades to one of said flanges and an edge of the other blade to the other flange, said blades being arranged to control air flow through said opening and movable toward and away from each other; and means for adjusting said damper blades comprising a damper operating lever having an outer end, a damper blade lever rigidly supported on one damper blade and having an unattached end, a link pivoted to said last lever and to the other damper blade, said damper operating lever being pivoted on and supported by said link, said operating lever having a portion extending beyond said link in an opposite direction from said outer end, and a second link pivotally connecting said unattached end of the damper blade lever to the extending portion of the operating lever and movable from a position in alignment with said portion of the operating lever to various angular

positions relative to said portion, said second link being resilient between its pivotal connections to lock said damper blades closed in an over-center position of the linkage.

- 5 9. In a register comprising a grille frame around an opening, a pair of damper blades hingedly mounted to swing within said grille frame and control air flow through said opening, a grille covering the front of said grille frame, linkage means for operating said damper blades comprising a damper blade lever secured to one blade, a link pivoted to said lever and to the other blade, a damper operating lever pivoted to said link, a link connection between said damper blade lever and said operating lever, said link connection being so arranged that pivotal movement of said operating lever causes a change in the relative angular positions of said damper blade lever and the link thereby varying the positions of said 10 damper blades, said linkage means being entirely supported by the damper blades, said grille having a slot through which said damper operating lever extends, and an adjustable stop in said slot for limiting the movement of said operating lever 15 and thereby determining the maximum open position of said damper blades.

10. In a register comprising a grille frame disposed around an opening, a pair of damper blades hingedly mounted for movement within said 20 grille frame for controlling said opening, a grille covering the front of said grille frame, linkage means for operating said damper blades comprising a damper blade lever secured to one blade, a link pivoted to said lever and to the other blade, a damper operating lever pivoted to said link and having a portion extending toward said damper 25 blade lever, and a link connection between said damper blade lever and said portion of the damper operating lever, said linkage means being thereby entirely supported by the damper blades, said damper operating lever extending through the front of said grille, said second link passing over-center for locking said damper blades in closed position and being shaped to provide for resiliency to permit of such passage over-center.

- 45 11. In a register comprising a grille frame disposed around an opening; a pair of damper blades hingedly mounted to swing within said grille frame for controlling said opening; a grille covering the front of said grille frame; and linkage means for operating said damper blades comprising a damper blade lever secured to one blade, a link pivoted to said lever and to the other blade, a damper operating lever pivoted to said link, a link connection between said damper blade lever and said damper operating lever, a portion of 50 said operating lever being arranged to pass through a position wherein it aligns with said link connection as said operating lever is moved from one of its extreme positions to another, said linkage means being thereby entirely supported by the damper blades, said damper operating lever extending through the front of said grille, and a spring connecting said damper blade lever to said first link and tending to retain said damper 55 blades open.

60 12. In a register, a grille frame disposed around an opening, a grille attached to said frame and extending over said opening, a boot assembly attached to said grille frame and having damper blades mounted thereon for controlling air flow through said grille frame and grille, said boot assembly including oppositely disposed boot ends, securing means formed in said boot ends, bracket means, turning vanes attached to said bracket

11

means, and a plurality of spaced attachment means formed in said bracket means for selectively and detachably connecting said bracket means and the attached turning vanes to said securing means and thus to said frame.

13. In a register, a grille frame, a grille thereon, damper blades attached to said frame for controlling the flow of air through said grille frame and grille, a turning vane assembly comprising a mounting bracket member and a turning vane attached to said member, a member having a rearwardly disposed flange attached to said grille frame, a pair of spaced ears secured to one of said members, and a plurality of pairs of notches formed in the other of said members for coaction with said ears, said turning vane being positioned in one location relative to said grille frame when one pair of notches coact with the pair of ears and being differently positioned when another pair of notches coact with the ears, said member also being readily disconnected if the turning vane is not needed.

14. In a register, a grille frame, a grille thereon, damper blades attached to said frame for controlling the flow of air through said frame and grille, said register being adapted for association with a duct having a right angle bend, a turning vane assembly comprising a pair of mounting bracket members and a plurality of turning vanes connecting said bracket members together, a pair of rearwardly extending flange members attached to said frame and spaced apart a sufficient distance to coact with said bracket members, a pair of ears formed on each member of one pair of said members, and a plurality of pairs of notches formed in each member of the other pair of said members, said notches coacting with said ears to secure said turning vanes and their bracket members to said frame, an ear of each pair of ears being bendable, the plurality of pairs of notches permitting a selective positioning of the turning vanes at different distances from said frame to thereby permit the register to be used with either a thin or a thick duct.

15. In a register, a grille frame, a grille thereon, damper blades for controlling the flow of air through said grille, said register being adapted for association with a duct having a bend at the top of the duct, a turning vane assembly comprising a pair of mounting bracket members and a plurality of turning vanes connecting said bracket members together, a pair of sheet metal

12

members attached to said frame, a pair of ears on each member of one of said pairs of members, and a plurality of pairs of spaced selectively usable notches in each member of the other pair of members, said ears and notches coacting to detachably and selectively secure said turning vane bracket members to said frame in one or another of a plurality of positions to thereby permit the register to be efficiently used with either a thin or thick duct.

16. A register comprising a grille frame; a grille thereon; damper blades attached to said frame for controlling the flow of air through said grille frame and grille; said register being of the sort usable with a duct having a bend therein; and a turning vane assembly arranged to extend into such a bend and comprising a pair of mounting bracket members and a plurality of turning vanes connecting said bracket members together, a pair of spaced boot end members attached to said frame, a pair of ears formed in each member of one of said pairs of members, and a plurality of pairs of notches formed in each member of the other pair of members for selective coaction with said ears, said ears and notches coacting to adjustably secure said turning vane assembly to said frame.

HENNING S. HERMANSON.
FREDERICK D. JOESTING.
